UNITED STATES PATENT OFFICE.

JOSEPH K. LEIBING, OF NEWARK, NEW JERSEY, ASSIGNOR TO SPLITDORF ELECTRICAL COMPANY, OF NEWARK, NEW JERSEY.

MAGNETO IGNITION DEVICE.

Application filed July 21, 1919. Serial No. 312,426.

To all whom it may concern:

Be it known that I, JOSEPH K. LEIBING, a citizen of the United States, residing at Newark, in the county of Essex and State of New Jersey, have invented certain new and useful Improvements in a Magneto Ignition Device, of which the following is a specification.

This invention relates to ignition apparatus in which the movable element is moved so as to control or shift the direction of the flux without continuous rotation of the movable element. In the preferred form illustrated in the drawings attached hereto, the movable element is oscillated or rocked to produce the flux changes and the generation of the ignition spark.

It has been the common practice heretofore in ignition generators of this type, commonly referred to as oscillators, to maintain the circuit breaker controlling the ignition coil in a closed position during both the setting and working stroke up to the point where the circuit breaker opens to produce the maximum spark timed in relation to the firing stroke of the engine. As will be hereinafter pointed out by the diagrams and curves, the movement of the movable element from its normal stationary position to what is sometimes referred to as the cocked or working position, will generate a flow of current in the coil winding which acts to choke back the flux through the coil and then at the higher speeds is not given sufficient time for the flux to reverse and build up current through the coil in the direction to produce a proper spark. Heretofore this difficulty has been overcome to some extent by making the ignition machine large and providing it with a very powerful magnetic field so the spark produced will still be great enough to fire an engine under ordinary conditions.

It is the object of my invention to provide an ignition generator in which this difficulty is overcome, that is to say one in which the flux is so controlled as to produce a very hot spark under all conditions of operation and at the same time resulting in a machine much simpler, lighter and less expensive than those used heretofore.

Other and further objects will be apparent to one skilled in the art after a study of the

specification taken in connection with the annexed drawings, wherein—

Figure 1 illustrates diagrammatically the application of my invention to an ignition generator of the inductor type.

Figure 2 is a view similar to Figure 1 but with the parts in a different position of operation.

Figure 3 shows a circuit breaker and cam in different position from that shown in Figures 1 and 2.

Figure 4 is a view similar to Figure 3 but with the parts in a different position.

Figure 5 is a perspective view of the circuit breaker used in connection with my invention.

Figure 6 is a view of one portion of the cam shown in the previous figures.

Figure 7 is a view of another portion of the cam.

Figure 8 is a washer used to hold the two portions shown in Figures 6 and 7 together and

Figure 9 is a screw used for holding the cam in position on the operating shaft.

Figure 10 is a resilient member connected between the cam portions shown in Figures 6 and 7.

Figure 11 is a copy of an oscillograph record taken from a given type of an ignition generator under a certain condition.

Figure 12 is a similar record of the same ignition generator under another condition, while

Figure 13 shows another condition of operation of the same machine.

Figure 14 is the same machine operated in the same condition as shown in Figure 1, but having my invention applied thereto.

Figure 15 is the same machine with my invention applied thereto under another set of conditions, and

Figures 16 and 17 illustrate the same machine under still other conditions.

Referring now to the details, wherein like numbers refer to corresponding parts in the various views, 1 and 2 illustrate the field poles of a magnetic field structure across which the core 3 is placed. Core 3 is illustrated as having a low tension winding 4 and a high tension winding 5. A spark gap 6 illustrating a plug in an engine cylinder is connected in circuit with the high tension

winding 5. The breaker box 7 for attachment to one end of the ignition generator carries a stationary insulated block 8 carrying an adjustable contact 9. A movable member 10 carries a contact 11 adapted to cooperate with contact 9. Member 10 is preferably grounded as indicated. Between the field poles 1 and 2 an inductor having lobes 12 and 13 is adapted to operate. This type of inductor and its manner of distributing the flux through the field poles 1 and 2 and core 3 is illustrative of the well known "Dixie" type of ignition generator and since it is well illustrated and described in Patent 15 No. 1,081,760, issued December 16, 1913, to C. T. Mason, it will not be further described herein except in connection with my arrangement of control of the flux through the working coil. Attached to one end of the 20 operating shaft is a lever 14 which is held in a normal stationary position by springs 15 and 16, all in a well known manner. The lever 14 is adapted to be operated by a movable member 17 driven by the engine. On 25 the other end of the operating shaft is mounted a cam consisting of two portions, one portion shown in Figure 7 having a cam 18 with sleeve 19 loosely mounted on the shaft and held thereto by means of a pin 30 extending through the slot 20, one end of the pin is adapted to engage the eyelet 21 of spring 22, the opposite end 23 of the spring is adapted to enter a hole 24 in cam 18. The 35 end of the operating shaft is reduced to receive a second portion 25 of the cam shown in Figure 6. This cam portion has a short hub 26 which extends within the opening 27 of the cam portion 18. A keyway 28 adapted to receive a key which is used in conjunction 40 with the washer 29 and screw 30 to fasten cam portion 25 to the end of the operating shaft. The cam portion 18 has a notch 31 which is adapted to be engaged by a metallic bumper 32 carried adjacent the fiber bumper 45 33 on the breaker arm 10. The metallic bumper 32 is preferably of steel and hardened so as to reduce the wear thereon.

Coming now to the operation of my device and assuming the parts to be in the normal 50 or stationary position shown in Figure 1, it will be noted that the circuit breaker points 9 and 11 are held open by both portions 18 and 25 of the cam engaging the bumpers 32 and 33. As the movable element 55 is moved by the member 17 acting to the right against lever 14, it is seen that the rotor lobes 12 and 13 which in normal position direct the magnetic flux through the coils 4 and 5 in the direction of the arrow 60 shown in Figure 1, will produce a rate of change in this flux tending to set up a current in the primary winding 4, but this is prevented since the circuit contacts 9 and 11 are held apart. Further movement of 65 the lever 14 to the right carries the cam 25

to the position shown in Figure 3 but the cam 18 acting on the bumper 32 still holds the contacts 9 and 11 open until the lobes 10 and 13 have preferably passed out of operative engagement with the poles 1 and 2 and have moved into operative relationship with poles 2 and 1 respectively; that is to say, to a position in which the flux is reversed through the primary coil 4 as indicated in Figure 2. Directly after this flux reversal has taken place, the cam 18 moves to a point where the bumper 32 drops into the notch 31 allowing the circuit breaker contacts 9 and 11 to close, but since the flux through the primary coil has already built up, while the contacts 9 and 11 are open to substantially its maximum value ready for the return or working impulse, little or no current is generated and hence no choking effect is produced during the setting interval. Continued movement of the member 17 carries the lever 14 with the movable element to its full working position as shown in Figure 2 and as soon as the member 17 passes from engagement with the lever 14, the lever 14 together with the movable element is quickly restored to normal position due to the energy stored in the spring 15. At this time the cam portions 18 and 25 are in the position shown in Figure 2, but due to the engagement of the bumper 32 95 engaging the notch 31 of cam 18 this portion of the cam is held from rotation until the rotating element has reached the position of generating a maximum spark at which time 100 the cam 25 reaches the position shown in Figure 4, wherein it engages the bumper 33 to open the contacts breaking the circuit through the primary coil 4 which in turn acts on the secondary 5 to produce a spark 105 in the usual manner. As soon as the breaker arm 10 has been moved to open the contacts, as just explained, spring 22 acts to return the cam 25 to its normal position shown in Figure 1, ready for the next cycle of operation. From what has been said it will be readily understood that the choking action 110 present in ignition generators where the ordinary cam is used is eliminated and a hot spark is produced at various periods of 115 oscillation or movement of the movable element under various conditions of operation.

To illustrate more graphically the advantages of my invention, reference will be had to the curves illustrated in Figures 11 to 120 17 inclusive. Each of these figures are reproductions of oscillograph records taken from the same machine but in accordance with the notations marked on the curves associated with the different figure numbers. In each of the illustrations the curves marked T illustrate sections of a time interval curve automatically placed on the record by the oscillograph, the space between the peaks illustrating .001 of a second. In Fig- 125 130

ures 11, 12 and 13, the operation of a certain ignition generator with an ordinary cam is depicted, while Figures 14 to 16 inclusive illustrate the same ignition generator with my invention applied thereto; that is, one equipped with a cam as hereinbefore described. An ignition generator equipped with the regular cam would give no spark at all in a test gauge in which the pressure 10 was 125 pounds per square inch but the same generator when equipped with my improved cam gave sparks under this condition as illustrated in Figures 16 and 17. From these curves it will be clear how my invention has improved the sparking ability of 15 this particular ignition generator.

While I have shown the application of my invention to one form of ignition generator, it shall be understood that it may be used 20 with other forms of ignition generators, such as the so-called shuttle type. It will be further apparent that numerous changes and alterations may be made in the details for carrying out my invention and I therefore 25 do not wish to be limited to the exact form shown and described herein. Since the primary coil controls the functioning of the secondary coil, I have referred to the primary as the coil for producing the spark 30 and therefore do not wish to be limited to a construction which includes both primary and secondary coils as one coil only may be used and this connected to a wipe spark contact in the engine.

Having thus described my invention, what I claim is:—

1. In a device of the character described, a coil for producing a spark, means for energizing said coil including a magnetic field 40 and a movable element having a normal stationary position for directing magnetic flux through said field and coil, means for moving said movable element from said normal position to a working position, means 45 for preventing said coil from interfering with the movement of the magnetic flux during a considerable part of the movement of the movable element from normal to working position, means for utilizing the magnetic flux put into operation as the movable element reaches the working position and means for completing from the working position the working stroke of said movable member for the purpose described.
2. In a device of the character described, a coil for producing a spark, means for energizing said coil including a magnetic field and a movable element having a normal stationary position for directing magnetic flux 55 through said field and coil, means for moving said movable element from said normal position to a working position, a circuit breaker for controlling the working of said coil, a cam acting on said circuit breaker to hold said coil winding open to prevent gen-

eration of current therein during the early portion of the movement of the movable element from normal to working position, means for quickly completing the working stroke of the movable element and a cam for 70 acting on the circuit breaker near the end of the working stroke for the purpose described.

3. In a device of the character described, a coil for producing a spark, means for energizing said coil including a magnetic field and a movable element having a normal stationary position for directing magnetic flux through said field and coil, means for moving said movable element from said normal 80 position to a working position, a circuit breaker for controlling the working of said coil, a two part cam, one part acting in conjunction with said circuit breaker to hold said coil winding open to prevent generation 85 of current therein during a considerable part of the movement of said movable member from normal working position, the other part of said cam acting on the circuit breaker at the proper time to produce a 90 spark from said coil on the working stroke of said movable member and means for producing a quick working stroke of the movable member.

4. In a device of the character described, a coil for producing a spark, means for energizing said coil including a magnetic field and a movable element having a normal stationary position for directing magnetic flux through said field and coil, means for moving said movable element from said normal position to a working position, a circuit breaker having a movable member for controlling the working of said coil, said movable member having a two section bumper, 100 a cam having one part acting on one section of the bumper to hold the movable member of the circuit breaker in open position for a longer period than the other part of the cam acting on the other section of the bumper, whereby maximum energy may be stored in said coil and discharged on the working stroke of the movable element by the action of the second mentioned part of the cam acting on the second mentioned section of the bumper.

5. In an oscillating ignition generator having a sparking coil and a rotatable element having a drive shaft for producing changes of flux through said coil, an interrupter in circuit with said coil, a cam for operating the interrupter at the time when maximum energy is stored in said coil by the rotating element in its working stroke, and an auxiliary cam acting on said interrupter to hold said coil circuit open during the initial flux changes produced by the rotatable element in being moved to a position for its working stroke.

6. In an oscillating ignition generator 130

having a sparking coil and a rotatable element having a drive shaft for producing changes of flux through said coil, an interrupter in circuit with said coil, two interrupter cams operated by the shaft of said rotatable element, one cam being fastened directly to said shaft and moving in synchronism therewith and acting on said interrupter at the time when maximum energy 65
 10 is stored in said coil by said rotatable element in its working stroke and means for retarding the initial rotative movement of the other cam through a predetermined angle whereby said interrupter is held open until
 15 said rotatable element has moved a predetermined distance as and for the purpose described.

7. In an oscillating ignition generator having a sparking coil and a rotatable element 20 having a drive shaft for producing changes of flux through said coil, an interrupter in circuit with said coil, two interrupter cams operated by the shaft of said rotatable element, one cam being fastened directly to said 25 shaft and moving in synchronism therewith and acting on said interrupter at the time when maximum energy is stored in said coil by said rotatable element in its working stroke, means for retarding the initial rotative movement of the other cam through a 30 predetermined angle whereby said interrupter is held open until said rotatable element has moved a predetermined distance for the purpose described and means for restoring 35 said second cam to normal position during the working stroke of said rotatable element.

8. The method of producing sparking current from a coil associated with a field carrying magnetic flux and with means for shifting the direction of the flux through the coil, which consists in shifting the direction of the flux and during substantially all of said shift, acting on said coil to prevent 40 any action of the coil on said flux, then again shifting the direction of said flux and again acting on said coil at the instant of the maximum rate of change of flux to produce the sparking current.

50 9. The method of producing sparking current from a coil associated with a field carrying magnetic flux and with means for changing the amount of flux through the coil, which consists in producing an initial 55 change of flux through said coil and coincident therewith acting on said coil to allow said initial flux change to take place freely and without effect on the coil, then producing another change of the flux through said coil and utilizing in the coil the major portion of said change of flux to produce the 60 sparking current.

60 10. In combination with a high tension magneto of the oscillating type, of inter-

rupter mechanism controlling the circuit of the primary winding, said interrupter mechanism arranged to insure that the circuit of the primary winding is open during the major portion of the movement of the rotor in one direction, closed at the end of such 70 movement, remains closed during the major portion of the movement of the rotor in the opposite direction and opens near the end of such last movement, seriatim.

11. An oscillating ignition equipment consisting in combination with a magneto comprising a rotor, stator, and generating windings, spring means normally holding the rotor in a certain position with respect to the stator, a trip device operably connected with the rotor arranged to be engaged by an engine driven actuator, moved against the tension of said spring means and released, together with means arranged to insure that the circuit including the generating winding is open before the trip device is released as aforesaid and closed during the whole of the recoil of the rotor under the tension of said spring means.

12. An ignition magneto of the type 90 wherein a current is created in the magneto generating winding by the recoil of the magneto rotor under the tension of spring means after the latter has been cocked against the tension of the said spring means 95 and released, in combination with means arranged to insure that the circuit of the generating winding is open before the rotor recoils under the tension of its associated spring means as aforesaid and closed before 100 the recoil movement begins.

13. An ignition magneto of the type 105 wherein the current used for ignition purposes is created in the magneto generating winding by the recoil of the magneto rotor under the tension of spring means after the latter has been cocked against the tension of the spring means and released, in combination with an interrupter in circuit with the generating winding, said interrupter maintaining the circuit of the generating winding closed during the whole of the recoil of the rotor, and means for operating the interrupter to maintain the circuit of the generating winding in open condition 110 during the major portion of time immediately prior to the recoil of the rotor under the tension of said spring means.

14. In combination with an ignition magneto of the oscillating type, means arranged 120 to insure that the circuit including the magneto generating winding is open during a substantial portion of time prior to the recoil of the rotor and closed during the whole of the recoil of the rotor.

In witness whereof, I affix my signature.

JOSEPH K. LEIBING.
